BASE PLATE FOR A DENTAL ARTICULATOR

Graham Peter Rabey, "Greenbanks" Trout Rise,
Loudwater, Hertfordshire, England

Filed Aug. 29, 1969, Ser. No. 18,927

Term of patent 14 years

Claims priority, application Great Britain Mar. 3, 1969

Int. Cl. D24—01

U.S. Cl. D24—1

Fig. 1.

Fig. 2.

Fig. 3.

FIG. 1 is a perspective view of a base plate for a dental articulator, showing my new design;

FIG. 2 is a top plan view; and

FIG. 3 is an elevation to which the other elevations correspond.

I claim:

The ornamental design of a base plate for a dental articulator, substantially as shown.
